BRUSH HOLDER

Raymond A. Manny, New York, N. Y.

Application December 9, 1944, Serial No. 567,360

3 Claims. (Cl. 248—110)

The present invention relates to holders for shaving brushes.

The principal object of the invention is to provide a shaving brush holder which is at once simple and inexpensive to make, practical to use and which occupies unused space such as the space immediately below a wash basin shelf.

Another object is the provision of a shaving brush holder which holds the brush, bristles down, thus enabling the water to drain off more freely and to prevent the water from soaking into the brush handle. It should be noted that long continued presence of water in and about the bristles may produce an unsanitary brush and a rotting of the bristles and of the material in which they are set, a condition which soon causes the bristles to fall out.

A further object is the provision of a holder for shaving brushes which may be affixed to a fixture such as the one above mentioned without the use of such conventional means as screws or nails.

A preferred embodiment of the invention is shown in the accompanying drawing in which—

Fig. 1 is a perspective view of the holder shown attached to a shelf, a conventional shaving brush hanging from said holder;

Fig. 2 is a side view of said holder;

Fig. 3 is a vertical section on the line 3—3 of Fig. 2; and

Fig. 4 is a top view of said holder.

The shaving brush holder 10 shown in the drawing is made of a unitary length of metal wire or plastic material drawn to the form of metal wire, bent to appropriate shape. It comprises two side members each of which has an upper portion 11 adapted to receive a conventional removable glass shelf 13 and a lower portion 12 adapted, in association with the corresponding lower portion of the other side member, to receive and hold the handle 14 of a conventional shaving brush 15.

In side elevation, each side member is shaped to the outline of the letter T, having a long and narrow upper cross piece, above identified with the number 11, and a short and wide stem piece, above identified with the number 12, whose lower end 16 slopes downwardly slightly toward the rear. In plan elevation, the lower sloping portion of the stem piece takes the shape of a pair of frog's legs wide open at the front, indicated by the number 17, tapering inwardly toward the center to a constricted portion 18, widening out at the center and toward the rear to form a pair of facing concave portions 19 which draw to-

gether at the rear to form a second constriction 20, narrower than the first.

A bridge 21 having humped portions 22 at each end joins the two side members at the joint where the rear of the stem piece meets the top cross piece. The two ends of the metal wire which comprises the holder meet at the bridge at this point and are looped around the humps to support the rear portion of the stem piece and to prevent displacement of the rear portions of the two side members relative to each other.

The handle of the conventional shaving brush, as shown in Fig. 1, has a constricted center portion 23. It is this constricted portion that the holder above described grips. To utilize the holder, the brush is held bristles down and inserted through the opening 17 and constriction 18 into the space formed by the two concave portions 19. The diameter of the constricted portion 23 of the handle is substantially equal to the distance separating the two concave portions at their outermost parts. Since the head 24 of the brush is of a substantially larger diameter, downward displacement of the brush with respect to the concave portions 19 of the holder is prevented.

A preferred embodiment of the invention has hereinabove been described. It is clear that modifications may be incorporated therein without departing from the basic principles of the invention. Specifically, a slightly different shape of the side members may be had providing a mouth portion adapted to receive the handle of a conventional shaving brush, leading to a constricted portion adapted to hold the handle of a conventional shaving brush is formed therein. Other modifications may be incorporated therein as desired.

I claim:

40. 1. A holder for shaving brushes comprising a unitary wire-shaped member bent to form two side portions each of which has an upper portion adapted to slip over and hang from a conventional medicine cabinet type of removable shelf and a lower portion adapted in association with the corresponding lower portion of the other side portion, to receive and hold the handle of a conventional shaving brush.

50. 2. A holder for shaving brushes comprising a unitary wire-shaped member bent to form two side portions joined and held against displacement relative to each other by means of a bridge portion, said side portions being adapted to slip over and hang from a conventional medicine cabinet type of removable shelf, said side por-

tions being spaced and bent to provide a gripping means for the handle of a conventional shaving brush and a horizontal path of access of said handle to said gripping means.

3. A holder for shaving brushes comprising a unitary wire-shaped member bent to form two side portions joined at the rear by a bridge por-

tion, the upper parts of said side portions being adapted to slip over and hang from a conventional medicine cabinet type of removable shelf, the lower parts of said side portions being adapted to grip between themselves the handle of a conventional shaving brush.
